UNITED STATES PATENT OFFICE.

CHARLES RUSSELL HALL, OF CONGLETON, ENGLAND.

SIPHON.

Application filed October 6, 1924, Serial No. 742,028, and in Great Britain October 25, 1923.

This invention relates to siphons for drawing off water or other liquid from reservoirs or the like and discharging into mains or otherwise and is designed to provide that 5 the flow from the siphon may be continuous or may be checked and restarted as required without emptying the siphon or permitting air to be forced into it through the discharge end and causing an air lock therein.

10 According to the invention a sealed tank is placed at a convenient position at a lower level than the reservoir, with which the siphon connects and into which it discharges and to which an air shaft is fitted extending 15 above the level of the reservoir to permit of the escape of air and to maintain the pressure or head of water equal to that in the reservoir.

The invention will be fully described 20 with reference to the accompanying drawings in which it is illustrated as applied to a water supply.

Fig. 1 is a sectional elevation through an artificial embankment of a reservoir showing 25 the invention applied thereto.

Fig. 2 is a plan of same partly in section.

Fig. 3 is a sectional elevation of a natural lake or reservoir showing the invention applied thereto.

30 Figs. 4 and 5 are enlarged details of Fig. 3.

The invention may be applied to drawing off water from reservoirs either artificial or natural to service mains at a lower level.

35 In the construction shown in Figs. 1 and 2, one or more siphon pipes C are built into the wall or embankment A¹ less than 30 feet from the base with the short leg c of the siphon extending inwards into the reservoir A.

40 In the construction shown in Figs. 3 to 5, a chamber B is erected in the reservoir A to receive the short leg c of the siphon C.

45 At any convenient position below the level of the bottom of the reservoir A, a sealed tank D is erected. The discharge end c¹ of the siphon C is carried down and connected to the sealed tank D so that the siphon discharges into it. The tank D is also fitted

50 with an air shaft E which is carried above the highest level of the water in the reservoir A to permit of the escape of any air entering the tank from accumulation in the mains and to maintain the pressure or 55 head of water therein equal to the head of water in the reservoir A.

To the sealed tank D one or more outlet mains G are connected through which the water is drawn off and distributed.

The bottom of the tank D is at sufficiently 60 low level that the siphon C will freely discharge into it and the outlet main or mains G enter it at a higher level than the discharge end c¹ of the siphon so as always to maintain a sufficient depth of water therein 65 to seal the discharge end of the siphon and prevent air entering it and cause an air lock.

The sealed tank D discharges through the discharge aperture e of the main G and valve e¹ into the mains or otherwise and the discharge can be shut off or opened at any time without disturbing the working of the siphon.

A float controlled hinged inlet arm F may 70 be attached to the inlet arm c of the siphon to take in the water from any level in the reservoir and the siphon may itself be fitted with a suitable valve at c² by which to exhaust it of air or charge it with water.

In the construction shown in Figs. 1 and 2 when the reservoir is full the head of water above the siphon C will force the water down the siphons until the level of the siphons is reached after which the siphons will act in normal manner to draw off the water.

A siphon chamber B as in Figs. 3 and 4 may be constructed in the reservoir A with an inlet pipe F to contain the inlet end c of the siphon and its floating arm but this is not essential as the siphon may be fitted direct into the reservoir and the air shaft E is preferably carried alongside of the siphon discharge end c¹ though it may be placed in any other desired situation if raised to the necessary height.

This combination of siphon and sealed tank will enable reservoirs to be connected with mains without recourse to tunnelling or boring to draw off the water through the bottom.

A similar arrangement or construction of siphon may be applied to the drawing of other liquids such as chemicals from tanks or cisterns.

What I claim as my invention and desire to protect by Letters Patent is:—

1. Siphon apparatus for drawing off water from a reservoir into supply mains comprising a siphon the short leg of which is extended into the reservoir, a sealed tank disposed at a lower level than the bottom

of the reservoir with which the long leg of the siphon connects and into which it discharges, a draw off main from the sealed tank below the level of the said draw off main 5 being higher than the level of the discharge end of said long leg of the siphon and a permanently open air shaft fitted to the top of the sealed tank and extending above the water level of the reservoir to permit of the 10 escape of air and maintain a pressure or head in the tank equal to that in the reservoir.

2. In siphon apparatus for drawing off water from a reservoir the combination with 15 the wall of the reservoir or siphon discharge

pipes built therein at a distance of less than thirty feet from the base, a sealed tank below the level of the reservoir with which the long legs of the siphons connect, draw off mains from the sealed tank arranged at a 20 higher level than the mouths of the discharge legs of the siphons, a permanently open air shaft fitted to the top of the tank and extending above the water level of the reservoir and valves in the draw off mains 25 whereby the discharge from the sealed tank may be regulated.

In testimony whereof I have hereunto set my hand.

C. RUSSELL HALL.
